United States Patent Office.

WILLARD M. FULLER, OF CHICAGO, ILLINOIS.

Letters Patent No. 72,626, dated December 24, 1867.

IMPROVED AMALGAMATOR FOR ORES OF GOLD AND SILVER.

The Schedule referred to in these Letters Patent and making part of the same.

TO ALL WHOM IT MAY CONCERN:

Be it known that I, WILLARD M. FULLER, of the city of Chicago, in the county of Cook, and State of Illinois, have invented certain new and useful Improvements in Amalgamators, or Gold and Silver-Separators; and I do hereby declare that the following is a full, clear, and exact description of the same, reference being had to the accompanying drawings, making a part of this specification, in which—

Figure 1 is a side view, representing the cylinder in glass, and

Figure 2 a vertical section.

Like letters refer to the same parts in both figures.

The nature of my invention consists in the application of hydrostatic pressure to force the pulverized or prepared quartz or other substances containing gold or silver through a mercury-bath; in injecting such substances into the amalgamator from the bottom; in providing the cylinder with a series of conical plates; in a novel cut-off or stop; and in the several combinations hereinafter set forth and claimed as new.

To enable others skilled in the art to make and use my improved amalgamator or separator, I will describe its construction and operation.

The cylinder A is made of copper, and spheroidal in form; but I do not limit myself to material or form. Inside of this cylinder I insert, from the top the shaft E, which passes through the collar J, which collar is provided with a jacket, J', or cap, which is screwed down on to the collar, so as to secure the packing K in place. This shaft is also provided with a collar, H, and set-screw, by means of which the distance between G' and O is regulated or adjusted. On the outer end there is also provided a pulley or belt-wheel, I, by which the shaft is made to rotate. The revolutions of the shaft can be produced by any suitable or well-known means. Inside of the cylinder A, the shaft is provided with two or more (usually six) conical plates. The plates F are larger in diameter than plates G, and are provided near the shaft with holes N. The plates G are inverted as shown, and are without holes. The lower one, G', is attached to the end of the shaft, and made to fit the mouth O of pipe C. The cylinder or tub B may be made in any convenient form, and in use should be located somewhat higher than A, at its top, as shown. This tub is connected with the cylinder A by the pipe C, which passes down below the cylinder A, which cylinder it enters at the bottom. The discharge-pipe D is attached to the cylinder A near the top, and turned and carried down the required distance, as explained hereinafter. This pipe D, at its highest point, is provided with a short tube or cock, L, which is provided with a cut-off or stop, and with a bowl, M, at its top. This bowl may be covered with a cap or not, as desired. The lower end of the pipe D is also provided with a stop, (not shown.) The desired amount of mercury is placed in the cylinder A, and, when not in operation, a portion of it will stand in tube C.

In operation, the pulverized material, which has been previously suitably prepared, is placed in the tub B, mixed with water. The stop at the lower end of pipe D is closed, and the pipe filled with water through the short pipe L, which will also fill the space above the mercury in the cylinder A. When the lower end of the pipe D is opened, the flow of water through this pipe, acting as a siphon, tends to create a vacuum in the top of cylinder A containing the mercury, which causes a pressure upon the material in tub B, and forces it down through pipe C, and into the cylinder at O. The pulverized material is so finely comminuted, that it will carry freely in water, which rises through the mercury and fills the space above, so that the pipe D will continue to act as long as there is anything in the tub. Its operation can at any time be stopped by turning the stop at the lower end of pipe D, or by turning the screw in collar H, so as to let cone G' down on to the mouth O of pipe C, which latter mode will prevent a flow of mercury into pipe C; but when it is desired to stop for any length of time, the other mode is preferable, as the return flow of the mercury clears out the pipe C, and drives its contents back into the tub. The length of the pipe D will correspond with the height of the column of mercury, as a column of mercury twenty-eight inches in height will require a fall of thirty-two feet in pipe D to insure its operation, and the wider the departure from these points, the more rapid will be the operation; much less than this ratio will not operate. When the prepared material is passing through, it passes through mercury until it reaches G', against which it impinges, and by which it is spread. Passing off from this, it again passes through solid mercury till it comes in contact with F, by which it is returned to the shaft, and passes through the holes N, repeating the operation until it passes out of the mercury, and is carried off. This, with the rotations of the

shaft and plates, brings all of the mercury into use, and the plates F and G being of copper, an amalgam will be formed on them which will contain nearly all of the precious metals. The gold is separated from the mercury in any of the usual modes.

It will be seen from the operation that very much machinery is dispensed with in this amalgamator, as there are no pumps, screws, plungers, or the expensive devices required to force the material to the bottom of the mercury-bath, or insure its operation, as it moves with a steady and constant force, which will continue as long as the material is fed, thus making an amalgamator which is simple in its construction, efficient and inexpensive in operation.

Having thus fully described my invention, what I claim as new, and desire to secure by Letters Patent, is—

1. The application of a siphon to an amalgamator for producing a continuous current through the mercury, substantially as specified.
2. The siphon or pipe D, in combination with the cylinder A, substantially as and for the purposes specified.
3. The shaft E, in combination with two or more plates, F and G, substantially as specified.
4. The combination and arrangement of the shaft E, collar H, cone G', and mouth O, or end of pipe C, substantially as described.
5. The pipe L, when attached to the pipe D, substantially as and for the purposes described.
6. The tub B, pipe C, and cylinder A, in combination with the pipe D, substantially as specified.

WILLARD M. FULLER.
